UNITED STATES PATENT OFFICE.

ARTHUR A. FINNEY, OF CHICAGO, ILLINOIS, ASSIGNOR TO FRANK E. LIVERANCE, JR.,
OF GRAND RAPIDS, MICHIGAN.

TIMER-SECURING DEVICE.

Application filed April 24, 1920, Serial No. 376,296. Renewed April 17, 1922. Serial No. 553,928.

To all whom it may concern:

Be it known that I, ARTHUR A. FINNEY, a citizen of the United States of America, residing at Chicago, in the county of Cook 5 and State of Illinois, have invented certain new and useful Improvements in Timer-Securing Devices; and I do hereby declare the following to be a full, clear, and exact description of the invention, such as will 10 enable others skilled in the art to which it appertains to make and use the same.

This invention relates to a very simple and novel means for securing the timer contact element of the timer used on engines 15 of the Ford type on the timer shaft thereof, thereby eliminating several parts, reducing the cost of manufacture, and making the attachment and assembly of the timer especially easy. The usual means now used 20 is to thread the end of the shaft and make an opening therethrough, the contact element being placed over the shaft, a pin passed through the opening in the shaft to engage with the contact element and hold it 25 fixed relative to the shaft, a sheet metal cup-like member with an opening to pass the end of the shaft being placed against the timer contact element and partially over it so as to preclude escape of the pin, after 30 which a binding nut is put on the threaded end of the shaft and tightened against said sheet metal member to secure the parts in place. With my invention, a single device is used to take the place of the pin, the 35 cup-like sheet metal member and the securing nut, and at the same time the necessity of threading the end of the timer shaft is obviated. Furthermore, the device of my invention is absolutely secure against 40 movement of any kind as distinguished from the loosening and eventual disengagement of the binding nut from the shaft, and the device is exceptionally easy to put in place in attaching the timer contact element to the shaft thereby reducing the cost 45 of assembly and making it much easier to make an assembly of the timer construction particularly after a motor vehicle containing the engine is fully built with the radial- 50 tor in place in front of and close to the timer, this being of chief value in repairing or replacing timers on used vehicles.

My invention has for its primary object and purpose the production of a device 55 capable of attaining the above described

noted ends and one which is fully capable of indefinitely withstanding the work it is designed to do.

For an understanding of the invention, reference may be had to the following description, taken in connection with the accompanying drawing, in which,

Fig. 1 is an end elevation showing the timer shaft and contact element, with my invention applied thereto. 65

Fig. 2 is a vertical sectional view taken longitudinally through the timer construction shown in Fig. 1, and

Fig. 3 is an enlarged perspective view of the securing device of my invention. 70

Like reference characters refer to like parts in the different figures of the drawing.

The shaft 1 on which the contact element of the timer is mounted has a front 75 end 2 of somewhat reduced diameter through which an opening 3 is made. Over this end 2 of the shaft the timer contact element is placed, which includes a sleeve 4 from which an arm 5 projects and on which 80 a lever 6 is mounted. A contact roller 7 is mounted at one end of lever 6 while a spring 8 is attached to the opposite end of the lever and also to a second arm 9 which projects from the sleeve 4. The outer 85 end of the sleeve is slotted as indicated at 4^a so that the slots thus made in opposite sides of the sleeve may lie in alignment with the opening 3 in the shaft. This construction so far described is that commonly used 90 with Ford engines in the timing mechanism, being enclosed in practice in a timer casing having contacts against which the roller 7 bears as is well understood. My invention is applicable to this timer and to all others 95 made as substitutes for the regular Ford timer, all having the sleeve 4 slotted as at 4^a incorporated in their construction.

The securing device of my invention comprises a clip 10 of tempered steel which is 100 formed to closely clasp and grip the end 2 of the shaft, the clip being open on its underside so that it may be readily sprung over the shaft from above. Integral with the clip is a tongue which extends rearwardly 105 from the upper rear portion of the clip being bent upwardly to make a shoulder 11 and then back horizontally as indicated at 12. A pin 13 is connected at its upper end and depends from said horizontal portion 110

of the tongue as shown, and when the clip is applied to the shaft, the pin passes through the upper slotted opening 4^a in sleeve 4 and downwardly into the opening 3 5 in the shaft.

This construction of attaching or securing device attains all of the objects above enumerated. It is a unit and is applied as one by merely springing the clip over the shaft. 10 It is removed as a whole when desired. It obviates the need of threading the end of the shaft, though it is applicable to and fully workable with shafts which have already been threaded for the usual type of 15 securing members. It, accordingly, may be used as a replacement of the usual securing means whenever a contact element of the timer is removed from the shaft even though the shaft is threaded and is applicable for 20 repairs in constructions now made. The shoulder 11 cones directly at the end of the sleeve 4 and together with the pin serves as a stop to prevent any endwise movement of the contact element along the shaft, while 25 the pin precludes any rotative movement of the sleeve on the shaft. Three separate parts are replaced by one and in new constructions the threading of the shaft is not needed. The invention is defined in the app- 30 pended claims and I consider myself entitled to all constructions which fall within their scope.

I claim:

1. In combination with a timer shaft hav- 35 ing an opening therein, a timer contact element mounted on the shaft and including a sleeve passing over the shaft slotted at one end to aline with the opening in the shaft, of a retaining member comprising a clip of 40 spring metal adapted to spring over the shaft, an integral off-set tongue extending from the upper portion of the clip over the slotted end of the sleeve, and a pin fixed to and depending from the tongue and pass- 45 ing through the slot in the sleeve and the opening in the shaft, substantially as described.

2. In combination with a timer shaft hav- 50 ing an opening therein, a timer contact ele- 50 ment mounted on the shaft and including a sleeve passing over the shaft, said sleeve

having one slotted to aline with the opening in the shaft, of a means to hold said contact element against detachment from or rotation on the shaft comprising a single 55 spring clip clasping the shaft and a pin connected thereto to enter the opening in the shaft and pass through the slotted end of the sleeve, substantially as described.

3. A securing device for timer contact ele- 60 ments, comprising a spring clip open at one side to spring over a timer shaft, a tongue extending laterally from the upper portion of the clip, said tongue being bent up- 65 wardly from the clip and then horizontally, and a pin attached to and depending from the end of the tongue, substantially as de- 70 scribed.

4. A securing device for timer contact ele- 75 ments, comprising a spring clip open at one side to spring over a timer shaft, a tongue ex- 80 tending from the clip at a point substan- tially opposite the open side thereof, and a pin attached to and extending from the tongue and substantially paralleling a dia- 85 meter of the clip.

5. In combination, a timer shaft, a timer contact element including a sleeve mounted on the shaft, said shaft having an opening therein and said sleeve being slotted at one 80 end to aline with the opening, and a single unitary device detachably connected to the shaft and having a part entering the opening in the shaft and through the slotted end of the sleeve to thereby secure the contact 85 element on shaft and hold the same against rotation with respect to the shaft, substan- tially as described.

6. A device of the character described comprising a substantially circular spring 90 clip open at one side, an integral tongue on the clip extending rearwardly therefrom at a point substantially opposite to the open side of the clip, said tongue being bent upwardly to form a shoulder and then to the rear, and a 95 pin connected at its upper end to the end of the tongue and depending therefrom back of the clip, substantially as and for the pur- poses described.

In testimony whereof I affix my signature. 100

ARTHUR A. FINNEY.
